(57) **CLAIM**

The ornamental design for a housing for a bone vibrating transducer for a communications headset, as shown and described.

DESCRIPTION

FIG. 1 is a perspective view of a housing for a bone vibrating transducer for a communications headset according to the present invention including a holster for receiving an earpiece which is shown in phantom lines and which is shown tethered to said housing;

FIG. 2 is a perspective view similar to FIG. 1 showing in phantom lines the earpiece secured in the ear of a wearer;

FIG. 3 is a top plan view thereof;

FIG. 4 is a front view thereof;

FIG. 5 is a right side view thereof;

FIG. 6 is a rear view thereof;

FIG. 7 is a left side view thereof; and,

FIG. 8 is a bottom plan view thereof.

The broken lines form no part of the claimed design.
